SUPPORT FRAME ASSEMBLY FOR
SEAT BEDS

Frank J. Mis, Chicago, Ill., assignor of fifty per cent to Sealy, Incorporated, Chicago, Ill., a corporation of Delaware, and fifty per cent to Harris Hub Bed and Spring Company, Cicero, Ill., a corporation of Illinois

Application July 22, 1949, Serial No. 106,125

18 Claims. (Cl. 5—13)

1

This invention relates to certain new and useful improvements in support frame assemblies used in conjunction with convertible articles of furniture, which may be characterized as seat beds, and which are of the general type adapted in extended position to be used as a bed and to be folded from that bed position to a folded position in which they are adapted to be used as a seat, such as a chair or sofa, and may be reversely unfolded to the extended bed position.

This invention is a further variation of and improvement on the invention in Support Assemblies for Seat Beds shown and described in co-pending application Serial No. 90,127, now Patent No. 2,576,677.

This invention particularly relates to a new and novel means of concurrently operating the supporting legs associated with the device and to new and novel bracing means, both of which may be used in conjunction with an assembly of the type generally shown and described in the above identified co-pending application.

The principal object of the invention is to provide a seat bed which operates with superior ease and efficiency.

A further object of the invention is to provide a seat bed which includes a support frame assembly comprising a plurality of sections, front and intermediate legs, and leg operating toggle means constructed and arranged to concurrently operate said legs.

A further object of the invention is to provide new and novel leg operating means for a seat bed support assembly.

A further object of the invention is to provide bracing means adapted in extended position of certain of the sections of the supporting assembly to prevent movement of those sections beyond horizontal co-planar position and further adapted in folded condition of the support assembly to serve as a corner brace therefor, limiting relative movement between the sections with which it is associated.

A further object of the invention is to provide a seat bed having a foldable and extendible support assembly which includes new and novel bracing means.

And a further object of the invention is generally to improve the design, construction, efficiency, and operation of convertible objects of furniture of the character described.

The means by which the foregoing and other objects of the present invention are accomplished and the manner of their accomplishment will readily be understood from the following

specification upon reference to the accompanying drawings, in which:

Fig. 1 is a fragmentary plan view of the support assembly of the present invention in extended bed position.

Fig. 2 is a side elevational view of the device in the position of Fig. 1.

Fig. 3 is a side elevational view illustrating the device in an intermediate folded position.

10 Fig. 4 is a side elevational view of the device in a further intermediate folded position.

Fig. 5 is a side elevational view of the device in fully folded seating position.

15 Fig. 6 is a fragmentary interior elevational view on an enlarged scale illustrating the bracing means of the invention, with the device in the position of Fig. 4 or Fig. 5.

Fig. 7 is a similar view of the same parts when the device is in the position of Figs. 1 and 2, or 20 Fig. 3; and

Fig. 8 is a fragmentary sectional plan view, taken as on the line VIII—VIII of Fig. 7.

Referring now to the drawings in which the various parts are indicated by numerals, the present invention primarily relates to a convertible frame assembly adapted for use with a relatively fixed seat body 11 having in conventional manner suitable side arms and a back portion 13.

30 The support assembly comprises opposite side frames, each consisting of a plurality of frame members, which side frames are joined at their front and rear ends by transverse members 15, and the support assembly includes a conventional spring web 17 which spans from side to side and end to end of the assembly and is suitably attached in conventional manner to the side frames and to the transverse end members. The support assembly is adapted in the extended position shown in Figs. 1 and 2 to serve as a bed support, in which position a suitable foldable mattress 19 is supported thereon. The support is foldable from that extended position to a fully folded seating position (Fig. 5) in which a portion or section of the support assembly is positioned as

40 a support for a suitable, preferably removable seat cushion 21. The supporting assembly consists of a plurality of sections which are disposed in substantially horizontal co-planar relation when the support assembly is extended into the 45 illustrated bed position. These sections may be designated as a main end section 23, which forms the front end section of the support assembly in bed position, a rear section 25, a main intermediate section 27, hingedly connected at one end to the rear section 25 and having its opposite end

hingedly interconnected by a fold section 29, to the end section 23.

Each of the sections includes an opposite pair of side frame members and a portion of the spring web 17 which spans between such members. Each of the frame members is preferably formed of a suitable structural member, such as an angle member, and preferably includes in extended position a horizontally disposed lower flange and a vertically disposed outer flange, the attachment of the spring web 17 being preferably made to the lower horizontally disposed flanges of the frame members. As the device includes two substantially identical opposite side frames, each including one frame member from each section, like numerals are employed herein to indicate like parts, and the description will be primarily directed to one of the side frames.

Each side frame includes in section 23 a side frame member 31, the forward transverse member 15 being rigidly secured to the opposite frame members 31 adjacent the outer ends of the frame members. To the opposite end of frame member 31, one end of a side frame member 33 of fold section 29 is hingedly attached, frame member 33 extending rearwardly therefrom and at its opposite end having the forward end of a side frame member 35 of the main intermediate section 27 likewise hingedly attached, and similarly a side frame member 37 of rear section 25 is pivotally attached to the rear end of frame member 35. At the opposite end of frame member 37 an arm 39 is rigidly attached and disposed angularly to the frame member 37, the arm 39 being pivoted in suitable fashion to the chair body 11 as at 41.

Adjacent the forward end of the assembly a front leg 43 is pivotally attached to side frame member 31 of section 23 and extends vertically therefrom in bed position of the assembly and is of a length to seat upon the floor or other support surface and thereby effect support of the outer end of the extended assembly. Preferably this point of pivotal attachment of leg 43 to member 31 is eccentric or off center in that it is forward of the mid line of leg 43 when that leg is vertical. Above the extended frame member 31, leg 43 is provided with a rearwardly projecting portion 45, which, in the vertical position of leg 43, lies substantially horizontal and parallel to but above frame member 31, and is positioned to engage mattress 19 to limit lateral movement thereof in bed position. Preferably portion 45 is formed integrally with leg 43, although obviously they may be formed separately and rigidly attached in suitable manner as desired.

A bracket 47 is rigidly fixed to frame member 33 of fold section 29, preferably adjacent the pivot between member 33 and end frame member 31. Pivoted to bracket 47 is a middle leg 49 which in extended bed position of the device extends vertically below the bracket 47 and is of a length to extend therefrom to seat upon the floor or other support surface so as to afford support of the assembly intermediate the length thereof in extended bed position.

Pivoted to frame member 31 intermediate its length is one end of a lever 51, the opposite end of which is articulately joined, as at 52, to one end of a second lever 53. The opposite end of lever 53 is pivoted to frame member 33 as by a pin 55 adjacent the pivotal attachment between frame member 33 and frame member 35, the pin 55 being preferably provided with an inwardly extending portion 55A, which is of a length to extend inwardly beyond the vertical flange of mem-

ber 33 and is arranged to act as a stop as hereinafter described.

It will be seen that the levers 51, 53 being articulately joined and connected to separate sections of the assembly are enabled to act as a toggle, this action being adapted among other things to effect control of the legs 43, 49. In order to enable the toggle, consisting of levers 51, 53, to control the movement of front leg 43, a link 61 is provided which is pivoted at one end to the free rear end of front leg portion 45, at its opposite end pivoted to toggle lever 51 intermediate the length thereof, thereby operatively coupling leg 43 to the toggle. Middle leg 49 is operatively coupled to the toggle by a link 59, one end of which is pivotally attached to leg 49 intermediate its length and the opposite end is pivoted to toggle lever 53 between pin 55 and joint 52.

Pivoted to frame member 33, preferably slightly forward of the mid point of that member, is one end of a link 61 which extends rearwardly therefrom and is pivotally joined, as at 62, to a short second link 63, the opposite end of link 63 being pivoted to frame member 35 rearward of the pivotal attachment between member 35 and member 33. When sections 27 and 29 are in coplanar position with members 33 and 35 in substantial alignment the lower edge of link 61 intermediate its length bears against the inwardly projecting stop portion 55A, which lies in the path of movement of link 61, this engagement limiting downward movement of link 61. Rearward of the point of attachment of link 63 to frame member 35 the upper and forward end of an elevator arm 65 is pivoted, the elevator bar being turnably carried in suitable fashion by a member, such as plate 67, which is secured to the chair body 11. Preferably a tension spring 69 is attached to the elevator bar 65 beyond the attachment of bar 65 to plate 67, spring 69 being oppositely attached to a suitable member, such as an angle member 71, which is rigidly fixed to the chair body 11.

When the device has been assembled as above described, it may be folded from extended bed position through various intermediate positions to the fully folded position indicated in Fig. 5, in which each section is positioned substantially perpendicular relative to the adjacent section or sections to which it is connected.

In accomplishing this folding the main end section 23 is lifted about its pivotal connection to the fold section 29 and is moved to the position illustrated in Fig. 3, in which frame members 31 of section 23 are moved to a position substantially at right angles to the members 33 of fold section 29. As the frame members 31 are moved relative to the frame members 33, the toggle levers 51, 53 are moved about their respective pivotal attachments to the frame members 31, 33 and are effective through the operative couplings by leg links 57, 59 to concurrently effect the folding of both the front leg 43 and middle leg 49.

It will be seen that the toggle action of the articulated levers 51, 53 through the link 57 is effective to act upon the leg extension 45, moving that leg extension to a position in which it is substantially perpendicular to frame member 31 and moving leg 43 to a position in which it is parallel to frame member 31 and lies therealong, with link 57, substantially parallel to member 31 and spaced therefrom. Leg 43 when thus folded lies alongside the originally upper edge of frame member 31, but does not extend beyond the

originally lower edge of that frame member due to the off-center pivotal attachment of the leg to member 31.

The folding of leg 43 through the action of the toggle levers 51, 53 on link 59 moves the leg into parallelism with frame member 33 of the fold section, in which position it is spaced a minor distance from the frame member.

When the device has been moved to the position illustrated in Fig. 3 the entire leg support, previously accomplished by legs 43, 49, is removed through the desired concurrent folding of those legs. At this point, as illustrated in Fig. 7, the bracing links 61, 63, together with stop member 55A, are effective to maintain frame members 33, 35 in horizontal co-planar alinement, the engagement of the lower edge of link 61 with stop 55A preventing downward movement of the lever beyond that point, the short link 63 retaining the pivot point 62 against such movement.

Further folding of the device moves frame member 33 about its pivotal connection to frame member 35, moving the device to the position illustrated in Fig. 4. As this movement is accomplished toggle levers 51, 53 and legs 43, 49 continue in their same positions relative to frame members 31, 33 and the two sections 23, 29 are thereafter moved together as a unit. When the device has been moved to the position of Fig. 4, toggle member 53 is disposed parallel to and lying along the upper edge of frame member 35 in edge abutment therewith. Toggle lever 51 is disposed substantially vertically between toggle joint 52 and frame member 31, serving to maintain the spacing of frame member 31 from the toggle joint, and accordingly from frame member 35.

During this movement of sections 23, 29, links 61, 63 are folded about their pivot 62 to the position as illustrated in Fig. 6, in which link 63 lies along and in edge abutment with the horizontal flange of frame member 35 and link 61 is disposed diagonally extending from its pivotal attachment to frame member 33 downwardly and rearwardly to the pivot 62, effecting a corner brace between frame members 33 and 35. Further movement of the device accomplishes completion of the movement to the position of Fig. 5, in which movement frame member 35 moves about its pivotal attachment to frame member 37, sections 23, 27, 29 being moved as a unit, tilting upwardly at the forward end and thence downwardly and rearwardly. In this action the elevator bar 65 is swung rearwardly and downwardly guiding and assisting in this movement of the folded sections. Rear frame member 37, together with arm 39 is moved about pivot 41 to the position illustrated in Fig. 5, in which frame member 37 is disposed substantially vertically at the rear of the device. It will be seen that these movements have accomplished the inversion of end section 23 so that the section 23 is disposed as an inverted horizontal section in which the originally under side of the section is disposed uppermost and is positioned to receive and support suitable cushion means 21.

Fold section 29 is disposed as a front substantially vertical section, and main intermediate section 27 is disposed in a horizontal position low within the seat body underlying and spaced below the upper seat supporting main end section 23. When in the fully folded position links 61, 63 are disposed to brace the corner between frame members 33, 35 and to prevent relative movement of those members beyond the relative position of substantial perpendicularity. The edge abutment of lever 53 with the upper edge of frame member

35 cooperating with lever 51 is effective to accomplish bracing of frame member 31, preventing movement of that frame member beyond its position substantially perpendicular to frame member 33.

It further will be seen that leg extension 45 and link 57, when moved by the toggle 51, 53 to position leg 43 parallel to frame member 31, are positioned to engage mattress 19 so as to prevent lateral movement thereof.

When it is desired to extend the device from the fully folded position, shown in Fig. 5, to return to extended bed position, the front of the folded device may be lifted, moving sections 23, 27, 29 about the pivotal connection between members 35, 37, during which action the movement of the elevator bar 65 is reversed, the arm moving upwardly and forwardly and being assisted in this movement by spring 69. The device is returned to the position shown in Fig. 4, in which frame members 37, 35 are moved into alinement, disposing sections 25, 27 in co-planar relation.

Further unfolding movement returns the device to the position of Fig. 3, moving section 29 into co-planar relation with sections 25, 27 and similarly alining frame members 33 with frame members 35, 37. The relative movement to alinement between frame members 33, 35 moves links 61, 63 to the position illustrated in Fig. 7 in which the lower edge of link 61 is brought into movement limiting engagement with stop 55A. In this manner movement of frame member 33 beyond alinement with frame member 35 is prevented and the engagement between link 61 and stop 55A is effective to retain these frame members and consequently sections 27, 29 in alined co-planar relation.

Further unfolding moves section 23 downwardly into alinement with the other sections, this unfolding movement causing the toggle, consisting of levers 51, 53, acting through links 57, 59, to accomplish concurrent unfolding of legs 43, 49 during movement of frame member 31 relative to frame member 33, the movement of frame member 31 through the final arc of ninety degrees being effective to accomplish the full unfolding of both legs, disposing them in vertical position to reengage the floor or other support surface and accomplish support of the extended device in bed position.

I claim:

1. In a support assembly for a seat bed which assembly includes in extended position a plurality of sections horizontally disposed in co-planar relation, said sections being hingedly interconnected for relative folding movement between adjacent sections to a folded seating position in which each section is substantially perpendicular to the next adjacent section, and return unfolding movement, a vertical leg pivoted to one of said sections, a second vertical leg pivoted to another said section adjacent the first said section, a toggle comprising a pair of levers articulately joined, one of said levers being pivotally attached to the first said section and the other of said levers being pivotally attached to the said adjacent section, a link operative to fold the first said leg coupling the first said leg to the first said lever, said link being pivoted to an intermediate portion of said first leg, and a second link operatively coupling the second said leg to the second said lever, said toggle being effective during said relative folding between said two sections only to concurrently move said legs to a position in which each said leg is in

substantial parallelism with the section to which it is attached.

2. In a support assembly for a seat bed which assembly comprises in extended position a plurality of sections horizontally disposed in co-planar relation, said sections being hingedly interconnected for relative folding movement between adjacent sections to a folded seating position in which each section is substantially perpendicular to the next adjacent section, and return unfolding movement, and said sections including an end section forming the forward end of said assembly, and a fold section hinged to said end section, a vertical front leg pivoted to said end section, a vertical intermediate leg pivoted to said fold section, a toggle comprising a pair of levers articulately joined, one of said levers being pivotally attached to said end section and the other of said levers being pivotally attached to said fold section, a link operatively coupling said front leg to the first said lever, and a second link operative to fold said intermediate leg coupling said intermediate leg to the second said lever, said second link being pivoted to an intermediate portion of said intermediate leg, said toggle being effective during said relative folding between said end and fold sections only to concurrently move said legs to a position in which each said leg is in substantial parallelism with the section to which it is attached.

3. In a support assembly for a seat bed which assembly comprises in extended position a plurality of sections horizontally disposed in co-planar relation, said sections being hingedly interconnected for relative folding movement between adjacent sections to a folded seating position in which each section is substantially perpendicular to the next adjacent section, and return unfolding movement, and said sections including a forward end section and a fold section adjacent and hinged to said end section, a vertical front leg pivoted to said end section, a vertical intermediate leg pivoted to said fold section, a toggle comprising a pair of levers articulately joined, one of said levers being pivotally attached to said end section and the other of said levers being pivotally attached to said fold section, a rearwardly projecting portion integrated with said front leg and lying above and substantially parallel to said end section, a link operatively coupling said portion to the first said lever, and a second link operative to fold said intermediate leg coupling said intermediate leg to the second said lever, said second link being pivoted to an intermediate portion of said intermediate leg, said toggle being effective during said relative folding between said end and fold sections only to concurrently move said legs to a position in which each said leg is in substantial parallelism with the section to which it is attached.

4. In a support assembly for a seat bed, which assembly comprises a plurality of sections hingedly interconnected for relative folding from extended bed position, in which said sections are disposed in horizontal co-planar relation, to folded seat position in which each said section is disposed substantially perpendicular to the adjacent said section, and return unfolding movement, said sections including in said seat position an upper horizontal seat supporting section, a lower horizontal section underlying and spaced below said upper section and a front vertical section extending between said horizontal sections; bracing means which consist of a

link pivoted at one end to said front vertical section and extending diagonally downwardly and rearwardly therefrom, a second link pivoted at its forward end to said lower section and lying along said lower section in edge abutment therewith, the opposite end of the first said link being pivotally attached to the rearward end of said second link to form a diagonal brace limiting relative folding movement between said front vertical section and said lower horizontal section, a stop carried by said front vertical section, said return unfolding movement moving said front vertical and lower horizontal sections into alignment and extending said pivotally joined links, the lower edge of said first link abutting said stop in aligned condition of the last mentioned said sections, to limit unfolding movement of said sections beyond said alignment.

5. In a support assembly for a seat bed, which assembly comprises a plurality of sections hingedly interconnected for relative folding from extended bed position, in which said sections are disposed in horizontal co-planar relation, to folded seat position in which each said section is disposed substantially perpendicular to the adjacent said section, and return unfolding movement, said sections including in said seat position an upper horizontal seat supporting section, a lower horizontal section underlying and spaced below said upper section and a front vertical section extending between said horizontal sections; bracing means which consist of a link pivoted at one end to said front vertical section and extending diagonally downwardly and rearwardly therefrom, a second link pivoted at its forward end to said lower section and lying along said lower section in edge abutment therewith, the opposite end of the first said link being pivotally attached to the rearward end of said second link to form a diagonal brace limiting relative folding movement between said front vertical section and said lower horizontal section, said return unfolding movement moving said front vertical and lower horizontal sections into alignment and extending said pivotally joined arms.

6. In a support assembly for a seat bed, which assembly comprises a plurality of sections hingedly interconnected for relative folding from extended bed position in which said sections are disposed in horizontal co-planar relation, to folded seat position in which each said section is disposed substantially perpendicular to the adjacent said section, and return unfolding movement, said sections including in said seat position a vertical section and a horizontal section connected thereto; bracing means which consist of a link pivotally attached to said vertical section and extending from its said attachment diagonally across the connection between said vertical section and said horizontal section, and a second link coupling the first said link to said horizontal section, whereby said first link is effective to limit relative folding between said vertical section and said horizontal section beyond said perpendicular relation.

7. In a support assembly for a seat bed, which assembly is shiftable from extended bed position to folded seat position and includes in said seat position a vertical section and a horizontal section connected thereto, bracing means which consist of a link pivotally attached to one of said sections and extending from its said attachment diagonally across the connection between said vertical section and said horizontal section, and

a second link coupling the first said link to the other said section, whereby said first link is effective to limit relative folding between said vertical section and said horizontal section beyond perpendicular relation.

8. In a support assembly for a seat bed, which assembly comprises a plurality of sections hingedly interconnected for relative folding movement from extended bed position, to folded seat position, and return unfolding movement, said sections during said movements being shifted to a position in which two adjacent said sections are in co-planar alinement; bracing means which include a link pivoted at one end to one of said alined sections, a stop carried by said one section underlying and in edge abutment with said link intermediate the length of said link, a second link pivoted at one end to the other said alined section, the opposite end of said second link being joined to the opposite end of the first said link, said links and stop cooperating to limit relative unfolding movement between said alined sections and maintain said alinement.

9. In a support assembly for a seat bed, which assembly comprises a plurality of sections hingedly interconnected for relative folding movement from extended bed position, to folded seat position, and return unfolding movement, said sections including a front section, a rear section and a pair of sections intermediate said front and rear sections and during said movements being shifted to a position in which said intermediate sections are in coplanar alinement; bracing means which include a link pivoted at one end to one of said intermediate sections, a stop carried by said one intermediate section underlying and in abutment with said link intermediate the length of said link in alined condition of said intermediate section, a second link pivoted at one end to the other said intermediate section, the opposite end of said second link being joined to the opposite end of the first said link, said links and stop cooperating to limit relative unfolding movement between said alined intermediate sections and maintain said alinement.

10. In a support assembly for a seat bed, which assembly comprises a plurality of sections including a front section, a rear section and a pair of adjacent sections intermediate said front and rear sections, said sections being hingedly interconnected for relative folding movement from extended bed position in which said sections are alined, to folded seat position in which each section is perpendicular to the next adjacent section, and return unfolding movement, said sections during said movements being shifted to a position in which said intermediate sections are in co-planar alinement; bracing means which include a link pivoted at one end to one of said intermediate sections, a stop carried by said one intermediate section underlying and in abutment with said link intermediate the length of said link in alined condition of said intermediate sections, a second link pivoted at one end to the other said intermediate section, the opposite end of said second link being joined to the opposite end of the first said link, said links and stop cooperating to limit relative unfolding movement between said alined sections and maintain said alinement, folding movement to perpendicular relation between said adjacent intermediate sections moving said first link to a position diagonally across the connection between said intermediate sections and said second link to a position in alinement

with said other intermediate section, said links in said latter position being effective to limit relative folding movement between said intermediate sections and maintain said perpendicular relation in folded condition of said intermediate sections.

11. In a support assembly for a seat bed, which assembly is shiftable from and to extended bed position to and from folded seat position, and includes a pair of connected, adjacent sections, said sections during shift of said assembly being shifted to and from co-planar alinement, bracing means which consist of a link pivotally attached to one of said sections, a second link attached to the other said section, said links being pivotally joined and means carried by one of said sections engaging one of said links in alined condition of said sections, whereby to limit relative unfolding movement between said alined sections.

12. In a support assembly for a seat bed, which assembly is shiftable from extended bed position to folded seat position and includes in said bed position a pair of connected, adjacent sections arranged in co-planar alinement, bracing means which consist of a link pivotally attached to one of said sections, a second link coupling the first said link to the other said section, and means carried by one of said sections engaging the first said link in said co-planar alinement to limit relative unfolding movement between said alined sections.

13. In a support assembly for a seat bed, which assembly includes a pair of connected sections shiftable to and from extended bed position from and to folded seat position, said sections during said movements being shifted to and from a position in co-planar alinement; bracing means which include a link pivoted at one end to one of said sections, a stop carried by said one section underlying and in edge abutment with said link intermediate the length of said link in alined condition of said sections, means coupling said link to the other said section, said link and stop engagement limiting relative unfolding movement between said sections when alined and maintaining said alinement.

14. In a support assembly for a seat bed, which assembly includes a pair of connected sections shiftable from extended bed position to folded seat position, and return unfolding movement, said sections during said movements being shifted to co-planar alinement; bracing means which include a link pivoted to one of said sections, a stop carried by said assembly underlying and in edge abutment with said link intermediate the length of said link in alined condition of said sections, means coupling said link to the other said section, said link and stop engagement limiting relative unfolding movement between said sections when alined and maintaining said alinement.

15. A support assembly for a seat bed which comprises an end section, a fold section adjacent said end section, an intermediate section, said sections being hingedly interconnected for relative folding and unfolding movements to and from bed position, in which said sections are arranged in horizontal co-planar relation, from and to seating position, in which said end and intermediate sections are horizontal and vertically spaced and said fold section is vertical, said end section during said folding movement being moved to a fold position in which said end section is perpendicular to said fold section and said fold section is co-planar with said intermediate sec-

tion, said assembly during said unfolding movement being unfolded to a position corresponding to said fold position, a front leg pivoted to said end section, an intermediate leg pivoted to said adjacent fold section, said legs being perpendicular to said sections in said bed position, a pair of levers respectively pivoted to said adjacent end and fold sections and articulately joined to form a toggle, means coupling said front leg to the said lever pivoted to said end section, means coupling said intermediate leg to the other said lever operative to fold said intermediate leg, said coupling means being connected to an intermediate portion of said intermediate leg, said toggle and coupling means being effective during folding movement of said end section to said fold position to concurrently retract both said legs into parallelism with said end and fold sections respectively.

16. A support assembly for a seat bed which comprises an end section, a fold section adjacent said end section, an intermediate section, said sections being hingedly interconnected for relative folding and unfolding movements to and from bed position, in which said sections are arranged in horizontal co-planar relation, from and to seating position, in which said end and intermediate sections are horizontal and vertically spaced and said fold section is vertical, said end section during said folding movement being moved to a fold position in which said end section is perpendicular to said fold section and said fold section is co-planar with said intermediate section, said assembly during said unfolding movement being unfolded to a position corresponding to said fold position, a front leg pivoted to said end section, an intermediate leg pivoted to said adjacent fold section, said legs being perpendicular to said sections in said bed position, a pair of levers respectively pivoted to said adjacent end and fold sections and articulately joined to form a toggle, a link coupling said front leg to the said lever pivoted to said end section, a second link coupling said intermediate leg to the other said lever, said toggle and links being effective during folding movement of said end section to said fold position to concurrently retract both said legs into parallelism with said end and fold sections respectively, and bracing means effective to limit relative movement of said end and intermediate sections beyond co-planar alinement in retracted condition of said legs.

17. A support assembly for a seat bed which comprises an end section, a fold section adjacent said end section, an intermediate section, said sections being hingedly interconnected for relative folding and unfolding movements to and from bed position, in which said sections are arranged in horizontal co-planar relation, from and to seating position, in which said end and intermediate sections are horizontal and vertically spaced and said fold section is vertical, said end section during said folding movement being moved to a fold position in which said end section is perpendicular to said fold section and said fold section is co-planar with said intermediate section, said assembly during said unfolding movement being unfolded to a position corresponding to said fold position, a front leg pivoted to said end section, an intermediate leg pivoted to said adjacent fold section, said legs being perpendicular to said sections in said bed position, a

pair of levers respectively pivoted to said adjacent end and fold sections and articulately joined to form a toggle, means coupling said front leg to the said lever pivoted to said end section, means coupling said intermediate leg to the other said lever, said toggle and links being effective during folding movement of said end section to said fold position to concurrently retract both said legs into parallelism with said end and fold sections respectively, and bracing means consisting of a link pivoted to said fold section, a second link pivoted to said intermediate section and to said other link, stop means carried by said assembly, positioned to engage one of said links in said fold position, said link-and-stop means engagement being effective to limit relative movement of said fold and intermediate sections beyond co-planar alinement in retracted condition of said legs.

18. A support assembly for a seat bed which comprises an end section, a fold section adjacent said end section, an intermediate section, said sections being hingedly interconnected for relative folding and unfolding movements to and from bed position, in which said sections are arranged in horizontal co-planar relation, from and to seating position, in which said end and intermediate sections are horizontal and vertically spaced and said fold section is vertical, said end section during said folding movement being moved to a fold position in which said end section is perpendicular to said fold section and said fold section is co-planar with said intermediate section, said assembly during said unfolding movement being unfolded to a position corresponding to said fold position, a front leg pivoted to said end section, an intermediate leg pivoted to said adjacent fold section, said legs being perpendicular to said sections in said bed position, a pair of levers respectively pivoted to said adjacent end and fold sections and articulately joined to form a toggle, a link coupling said front leg to the said lever pivoted to said end section, a second link coupling said intermediate leg to the other said lever, said toggle and links being effective during folding movement of said end section to said fold position to concurrently retract both said legs into parallelism with said end and fold sections respectively, and bracing means consisting of a bracing link pivoted to said fold section, a coupling link pivoted to said intermediate section and to said bracing link, a stop carried by said fold section positioned to engage said bracing link in said fold position, said link and stop engagement being effective to limit relative movement of said fold and intermediate sections beyond co-planar alinement in retracted condition of said legs.
